UNITED STATES PATENT OFFICE.

BERRY A. BAXTER, OF MANSFIELD, OHIO, ASSIGNOR TO NEW METHOD STOVE COMPANY, OF MANSFIELD, OHIO, A PARTNERSHIP COMPOSED OF HENRY H. SANFORD, BERNHARD R. AHRENDT, EDWIN D. BAXTER, AND BERRY A. BAXTER.

METHOD OF MAKING HINGES FOR STOVE-DOORS OR THE LIKE.

1,143,023.

Specification of Letters Patent. Patented June 15, 1915.

Application filed June 6, 1914. Serial No. 843,432.

To all whom it may concern:

Be it known that I, BERRY A. BAXTER, a citizen of the United States of America, residing at Mansfield, in the county of Rich-
5 land and State of Ohio, have invented cer-
tain new and useful Improvements in Meth-
ods of Making Hinges for Stove-Doors or
the like, of which the following is a specifi-
cation.

10 This invention relates to certain new and useful improvements in method of making hinges for stove doors and the like, and the primary object of the invention is to provide an improved and simplified method of making
15 strong and effective stove door hinges which also possess the desiderata of economy in material and consequent reduction in cost of production.

Further the invention aims to provide a hinge which can be economically made of wrought iron or steel, so as to allow fusion with the sheet metal stove door.

In the drawings: Figures 1 and 2 are perspective views of the two parts which are to 25 form the completed hinge as same appear after cutting from the stock; Figs. 3 and 4 are similar views of the two parts after same have been shaped and prior to assembling; Fig. 5 is a perspective view of the parts as 30 sembed; and Fig. 6 is a front elevation of a stove door showing the hinges in position thereon.

In proceeding in accordance with the present invention, a pair of pieces 1 and 2 are 35 cut from the stock which latter is half-round wrought iron or steel, the pieces each being then similarly beveled at one end thereof at 3 in order to eliminate sharp edges where the pieces engage or are secured to the stove 40 door. The piece 1 is then offset at its opposite end at 4 and the opposite end of the piece 2 is bent at right angles at 5, whereupon the parts are assembled in the position depicted in Fig. 5 in which position, the in- 45 ner face of the right angular end 5 of piece 2 seats on the inner face of the offset end 4 of piece 1, the two pieces thus having their inner sides conjointly forming a right-angle and providing a completely circular hinge 50 pintle or trunnion 7, whereupon the ends 4 and 5 are then electrically welded at 8. The hinge being formed in the manner described,

is then applied to the ends of the stove door A and is electrically welded thereto on the lines D and E.

It is a well known fact that great difficulty is experienced in the welding of cast or malleable iron, and by making a hinge of wrought iron from two pieces of half-round stock, an economical hinge is provided 60 which readily fuses with the sheet metal door and obviates the difficulty and defects of welding cast or malleable iron. The half-round stock is economical and requires no alteration except as regards the beveling 3 65 and the offsetting and bending as hereinabove noted, whereby a hinge can be both easily, quickly, and cheaply produced, and possesses the advantage of ready welding with the sheet metal stove door. 70

What is claimed is:

1. The herein described method of making stove door hinges for wrought-iron stove doors which consists in cutting two pieces of half-round stock of wrought iron, then offsetting an end of one piece and in bending an end of the other piece at right angles, then in assembling and electrically welding said offset and bent ends to form a hinge trunnion of complete circular cross-section 80 extending from the half-round surface, the flat surface of the hinge being adapted to closely fit the corner of the wrought iron door and then being fused thereto by an electric current. 85

2. The herein described method of making stove door hinges for wrought iron stove doors which consists in cutting two pieces from half-round wrought iron stock and then in assembling and electrically welding 90 said pieces whereby the same conjointly form an angular hinge having a pintle extending from the half-round surface, the flat surface of the hinge being made to conform to the corner of the wrought-iron door and 95 then electrically welding the hinge to the door.

3. The herein described method of making stove door hinges for wrought-iron doors which consists in uniting the adjacent ends 100 of two pieces of half-round wrought-iron stock whereby said ends conjointly form a hinge pintle and have angular relationship and a flat surface to fit snugly the corner of

the wrought-iron door and then electrically welding the hinge to the door as described and set forth.

4. The herein described method of making a wrought-iron stove door hinge for use in combination with a wrought-iron stove door which consists in taking half-round stock of wrought-iron and cutting and bending two pieces thereof and electrically welding them together in angular relation to each other

and thereby forming a pintle and then electrically welding the hinge to a corner of said wrought iron door, as described and set forth.

In testimony whereof I affix my signature 15 in presence of two witnesses.

BERRY A. BAXTER.
